(57) **CLAIM**

The ornamental design for a fan blade for a ceiling fan, as shown and described.

DESCRIPTION

FIG. 1 is a front view of the fan blade for a ceiling fan showing my new design;

FIG. 2 is a rear view of the design of FIG. 1;

FIG. 3 is a side view of the design of FIG. 1;

FIG. 4 is another side view of the design of FIG. 1;

FIG. 5 is a view of the top of the design of FIG. 1;

FIG. 6 is a view of the bottom of the design of FIG. 1; and,

FIG. 7 is a perspective view of the design of FIG. 1.

The broken lines showing environmental structure in FIGS. 1, 2 and 7 is for illustrative purposes only and forms no part of the claimed design or a specified embodiment thereof.
